UNITED STATES PATENT OFFICE.

CHARLES WILLIAM WATSON, OF ST. KILDA, VICTORIA, AUSTRALIA.

MACHINE FOR SPACING, TENSIONING, AND COILING MATERIAL SUCH AS WIRE.

Application filed June 20, 1923. Serial No. 646,726.

To all whom it may concern:

Be it known that I, CHARLES WILLIAM WATSON, a subject of the King of Great Britain and Ireland, residing at 1 York Street, St. Kilda, in the State of Victoria, Commonwealth of Australia, have invented certain new and useful Improvements in a Machine for Spacing, Tensioning, and Coiling Material Such as Wire; and I do hereby declare the following to be a full, clear, and exact description of the invention, such as will enable others skilled in the art to which it appertains, to make and use the same.

15 My invention relates to mechanism by which material such as wire may be located in coiled form under tension and with the convolutions suitably spaced apart for various constructional purposes, one of which is to provide an internal reinforcement in a tubular concrete structure, not necessarily circular in cross section,—circular, oval, or irregular forms being producible.

20 Various advantages and applications of the invention will become apparent as this specification is perused. By way of example I shall refer to the production of a winding of wire upon an internal arrangement of structural members, which would 25 include a core. Such members carrying or retaining the winding would in the case illustrated be embedded in concrete or other plastic material, and the core would be removed when the object was to produce a 30 pipe or like hollow structure by the centrifugal process.

35 In the centrifugal manufacture of reinforced concrete structures difficulty and loss have been experienced owing to the reinforcement becoming displaced or deformed during the centrifugal action. The agglomerate covering the reinforcement has been thicker at some parts than at others and there has been longitudinal spreading of or alteration of pitch of the reinforcement helices or convolutions, as well as diametral variations. Structures (pipes for instance) so made have been found wanting in durability, unsuitable for resistance to

high internal pressure, and generally unreliable.

In the manufacture of helically reinforced hollow structures the distribution of the reinforcement and the pitch of the helices should be uniform, while the winding should be concentric with the external and internal peripheries of the agglomerate structure, and should not be liable to either displacement or deformation.

40 A suitable tension of reinforcement should be retained throughout, so as to produce structures of uniform strength.

45 My invention enables structures of great strength to be made having the tensioned reinforcement arranged to contact with keepers, bars, or retainers, both reinforcement and keepers or bars retaining a predetermined position, or substantially so, during and after the period of centrifugal consolidation.

50 I provide means for feeding to and positioning relatively to bars, or keepers or the equivalent, disposed around a core, a tensioned reinforcement, or plurality of reinforcements, in intimate contact with each 55 other or separated as required, having convolutions of predetermined pitch. The pitch is maintained or at will altered by mechanism controlling the rate of travel of a reinforcement carrier and the rotation 60 of the core portion of a rotor.

55 I also provide reinforcement spacing, feeding and securing means.

65 In the specification of a concurrent application for a United States Patent I have described and claimed an invention entitled "Reinforcements for concrete and the like" Ser. No. 646,725, filed June 20, 1923, and in the specification of another concurrent application for a United States Patent I have 70 described and claimed an invention entitled "Improvements relating to the manufacture of articles centrifugally," Ser. No. 646,727, filed June 20, 1923.

75 In the accompanying drawings an embodiment of the invention is diagrammatically illustrated as applied to the manufacture of a pipe by way of example. The

invention however is not limited thereto, or to details which obviously can be modified while keeping within the scope of my claims. Like reference characters designate corresponding parts in these views.

The figures are as follows:—

Figure 1 is a partly sectional elevation of reinforcement winding mechanism at the driving end.

10 Fig. 2 is in continuation of the Fig. 1 reinforcement winding mechanism, showing reel and gearing.

Fig. 3 is in continuation of the Fig. 2 reinforcement winding mechanism.

15 Fig. 4 is an end elevation, partly, sectional, of reinforcement winding mechanism, on line 4-4 Fig. 2.

Fig. 5 is a sectional elevation of details of part of Fig. 4 viewed at right angles thereto.

20 Fig. 6 is an end elevation (left hand) of reinforcement reel carrier.

Fig. 7 is an end elevation of screw shaft engaging mechanism.

25 Fig. 8 is an end elevation (right hand) of reinforcement reel carrier.

The mechanism shown by Figs. 1 to 4 resembles in parts a screw cutting lathe, there being speed change gear, driving gear, 30 and a screw traveling shaft. I use such mechanism to move a reinforcement distributor K.

Frames 100 and 101 are mounted on supports 102, and frame 100 has a head with 35 pulleys 118, and any suitable change gears 103, 108, 119, 110, 111. 104 are bearings which carry a screw shaft 106, which carries gear wheel 108. Bearings 105 support the carrying shaft 107.

40 The distributor K is traveled by shaft 106, and includes a back plate 127 having sides 125, 126. I employ in some cases an additional shaft, above shaft 106, the sides 125, 126 being extended so that the distributor receives the support of both shafts, and is simply traveled by shaft 106.

Frame 101 carries ordinary tail centering head gear including a screwed shaft 88 and hand wheel 89 to advance or retract head 90. Within a head 91 is a hollow shaft 92, free to rotate therein, formed integral with head 90 and having (see Fig. 1) clutch teeth 114 engaging the teeth 38 of an end forming member which I term a seat S.

55 Within the head 91 is a chamber 94 into which shaft 92 can be retracted, but retained in required position, by known locking gear operated by the handle 23. Within shaft 92, surrounding screw 88, is a sleeve 95 retractable by rotation of shaft 88, which winds through the threaded rear end of sleeve 95. At the forward end an annular recess 96 is formed into which the tail of screw 97 carried by hollow shaft 92 enters,

thus rotatably uniting said shaft to sleeve 95. 65

A shaft 112 (see Fig. 1) carries the head 113, having clutch members 114 co-acting with clutch members or teeth 38 on the seat S, or with any suitable recesses 37 to receive lifting hooks. By these heads 90, 113, 70 the seats S, core C, and any other desired members are rotatably carried, in assembled position.

Each arc 72 is part of a positioning ring and is of L or other suitable cross section. 75 As seen in Figs. 1 and 3, there is a fitting 78 secured to an arc 72, and 81 is a lever to hold a reinforcement wire end under it against fitting 78 temporarily when required, the lever being secured by a ring 83.

Fig. 2 and Figs. 4 to 8 show bearings 124, which sustain a removable reinforcement supply reel or drum 120, having ends 121, and shafts 122, 123 which revolve in bearings 124. Bearings 180, 181 support the distributor on screw shaft 106 and on carrying shaft 107, respectively. Upon the side of 125, are levers 128, 131, see Figs. 6 and 7, having pivots 139, 140 and jaws 129, 132 which have screw threaded faces to engage 80 the screw shaft 106; 130, 133 being intermeshing toothed quadrants. Lever 131 has an extension 134 to which is pivoted, as at 135, a threaded stem 136 carrying a locking nut 137. Lever 128 has (see Fig. 7) an extension 138 through a slot in which stem 136 enters.

By drawing lever 131 towards lever 128 the threaded ends 129, 132 engage screw shaft 106 by the action of quadrants 133, 130, 100 while by tightening nut 137 on extension 138 the levers are locked together, and on shaft 106. By loosening nut 137 and throwing it clear of extension 138, and imparting an outward movement, the quadrant 133, co-acting 105 with quadrant 130, throws jaws 132, 129 out of engagement with shaft 106, thus stopping the carrier.

On the end shaft 123 of the reel is a gear 141, coacting (see Figs. 4, 5 and 8) with a 110 gear 142 on a shaft 143 which is mounted in bearing 144, in the side 126, this shaft also carrying a tension drum 145. One end of a tension strap 146 is mounted on a pin 147 extending from the side 126, the other end being secured as by a screw to a screwed stem 150 passing through a bracket 151 on side 126. This stem carries a tightening wheel 152, by which pressure is adjusted on drum 145 and transmitted through gears 142, 141 to reel 120, thus controlling the tension of reinforcement R as it unwinds. The pressure on gear 142 being decreased or increased as required, and the unwinding regulated, a 120 reel can be removed and replaced at will, the tension remaining unaltered. This is important, as reels will become empty and can thus be changed. The end of the reinforce-

ment wire is secured by any approved means.

At intermediate points of the winding, wire ends (if any occur) can be knotted or otherwise united or secured to the retainers as desired.

Any suitable reversing gear may be employed to travel the reel to and fro; as a well known belt drive, or the usual reversing gear carried by the driving head and frame 100.

With reference to reinforcement a polygonal form will under centrifugal force tend to approach the circular, the reinforcement tension being thus increased, and slackness, if any, automatically eliminated. In order that the retainers, with their reinforcement, may be completely embedded in agglomerate, with a layer on their inner faces, as well as on all other faces, they may be spaced slightly from the core by spacing blocks *c* which may be either integral with them or separate from them and inserted, and either keyed to them or not. By such spacing blocks the retainers are placed in the annular space between the core and mold. Thus, when this space is completely filled with agglomerate, the retainers will be in the agglomerate at an appreciable distance inwardly, both from the inner and outer wall of the pipe or other hollow article.

Upon tightening of the ring segments 72 to retain the retainers *D* in position, ready to receive reinforcement *R*, this portion of the apparatus is inserted between clutches 113, 90 of the winding mechanism. Then when core *C* is rotated the reinforcement supply carrier 120 also travels, at predetermined speed, to deliver reinforcement *R* under predetermined tension in convolutions having a predetermined pitch, the object being to guard against all subsequent displacement of the reinforcement. When the required reinforcement has been positioned and the ends secured, the rotor thus formed may be removed.

By means of wires passed through holes in the retainers the latter may be held on the core if desired.

The process of operating the illustrated mechanism is as follows:

The core *C*, seats *S*, and any other desired parts as bars 48 are assembled and secured by nuts 50 and are then mounted between the heads 113, 90 of the winding mechanism, and the retainers *D* are positioned, with the aid of the ring formed of arcs 72. The reinforcement *R* is then distributed as described. These parts and others which therewith constitute the rotor are then removed from the winding machine.

The rotor is then placed on bearing members of a molding machine.

I claim:

1. In agglomerate structure production

apparatus, a core, a plurality of retainers located around said core, a revoluble distributor by which to position reinforcement wire bearing on said retainers and being movable lengthwise of the core at a regulated speed, means resisting the revolution of said distributor to tension said wire reinforcement, and means for fastening the ends of the wire.

2. In a machine for agglomerate structure production, a core, a guide shaft, a reinforcement distributor mounted slidably on said guide shaft, a screw shaft which is rotatable at a predetermined speed, means to engage the screw shaft so that the distributor shall be traveled at selected speed, means to disengage the same at will, and gear to apply predetermined tension to the reinforcement.

3. In agglomerate structure production apparatus, a perforated configuring core, a series of retainers of bar type, a reinforcement supply director adapted to be operated at predetermined speed, a rotatable screw shaft, for operating the same, and speed change gearing for driving said shaft to feed the said reinforcement into position.

4. In agglomerate structure production apparatus, a reinforcement tensioning means and a traveling reinforcement distributor reel and gearing which co-acts with the tensioning means, to deliver reinforcement wire into position and regulate its speed, pitch, and tension during the delivery.

5. In agglomerate structure production apparatus, a traveling reinforcement distributor having a removable reel, gear carried by said reel, arms to receive the reel, adjustable tension mechanism having gear interlocking with the gear carried by the reel, a rotatable screw shaft passing through the arms, intermeshing engaging and disengaging means to travel the distributor, and shafting passing through the arms.

6. In agglomerate structure production apparatus, a feed shaft, a guide shaft, a traveling reinforcement distributor reciprocal thereon, bearings carried by said distributor, means for operatively connecting said distributor to said feed shaft, means for securing said connecting means in operative relation, a rotatable reel having shafts rotating in said bearings, and tension elements in operative connection with the reel, restraining its rotation and producing required tension on reinforcement material delivered from said reel.

7. In agglomerate structure production apparatus, a perforate core through which agglomerate material may be fed centrifugally, a plurality of retainers mounted on said core in spaced relation relatively to said core and to each other, means for clamping said retainers in position, and

means for winding a reinforcing element spirally about said retainers.

8. In agglomerate structure production apparatus, a perforate core, a plurality of retainers mounted in spaced relation thereon, means for clamping said retainers in operative position, and means for winding a reinforcing element spirally about said retainers.

10 9. In agglomerate structure production apparatus, a perforate core, a plurality of retainers mounted in spaced relation thereon,

means for clamping said retainers in operative position, and means for winding a reinforcing element spirally about said core and retainers in regularly spaced relation and under constant predetermined tension. 15

In witness whereof I have hereunto set my hand.

CHARLES WILLIAM WATSON.

Witness:

GEORGE G. TURRI.
